(57) **CLAIM**

The ornamental design for a lint roller cover, as shown and described.

DESCRIPTION

FIG. 1 is a front view of the new design for a lint roller cover; FIG. 2 is a top view thereof;

FIG. 3 is a bottom view thereof;

FIG. 4 is a left side view thereof, a right side view being a mirror image thereof;

FIG. 5 is a top perspective view thereof;

FIG. 6 is a bottom perspective view thereof;

FIG. 7 is a cross-sectional view taken along line 7-7 of FIG. 2;

FIG. 8 is a cross-sectional view taken along line 8-8 of FIG. 2; and,

FIG. 9 is a perspective view thereof showing the lint roller cover with a lint roller.

The surface shading illustrated in the drawings is provided merely to highlight the contour of design; it is not intended to be illustrative of texture or gloss.
